United States Patent Office

Des. 197,192
Patented Dec. 24, 1963

197,192

COMBINED BOTTLE, BASE AND CAP

Arnold I. Lorenzen, Toledo, Ohio, assignor to Owens-Illinois Glass Company, a corporation of Ohio

Filed May 23, 1963, Ser. No. 75,016

Term of patent 14 years

(Cl. D58—8)

FIG. 2

I claim:

The ornamental design for a combined bottle, base and cap, substantially as shown.
